Patented July 4, 1967

208,040

HIGH SPEED MONORAIL COMMUTER VEHICLE

Philip S. Crawford, 111 Churchill Lane,
Fayetteville, N.Y. 13066

Filed Dec. 12, 1966, Ser. No. 4,990

Term of patent 14 years

(Cl. D66—1)

FIG. 2.

FIG. 1.

FIG. 4.

FIG. 1 is a view in side elevation of a high speed monorail commuter vehicle embodying my new design;

FIG. 2 is a top plan view of the vehicle;

FIG. 3 is a bottom plan view of the vehicle;

FIG. 4 is a view of the vehicle in front elevation;

FIG. 5 is a view of the vehicle in rear elevation; and

FIG. 6 is a perspective view of the vehicle.

The dominant features reside in the solid line portions.
I claim:

The ornamental design for a high speed monorail commuter vehicle, substantially as shown and described.
